(57) **CLAIM**

The ornamental design for the pruning tool extendable handle, as shown and described.

DESCRIPTION

FIG. 1 is a right side of a pruning tool extendable handle showing our new design, the handle is drawn broken away for indeterminate length;

FIG. 2 is a left side view of the pruning tool extendable handle.

FIG. 3 is a front view of the pruning tool extendable handle. FIG. 4 is a back view of the pruning tool extendable handle; and,

FIG. 5 is a right side perspective view of the pruning tool extendable handle.

The matter displayed in dashed lines indicates context and does not form any part of the claimed design.
